AMUSEMENT DEVICE

Frank K. Maitland, Hermosa Beach, Calif., assignor, by mesne assignments, to Exhibit Supply Company, Chicago, Ill., a corporation of Illinois

Application June 18, 1934, Serial No. 731,127

10 Claims. (Cl. 273—118)

My invention relates to an amusement device and contemplates the playing of a game thereon, the outcome of said game being dependent upon the skill of the player.

- 5 My invention relates to amusement devices, and has particular reference to game boards employing counters which may be distributed in various positions upon the board, the positions designating predetermined values.
- 10 Game boards employing a number of pockets, holes or other play-piece receptacles, distributed thereover to receive playing pieces projected upon the board, are well known, the most common form thereof being known as the "pin and marble" games, comprising, essentially, a playing board provided with a plurality of holes for the reception therein of balls which are projected upon the playing field by any suitable projecting device. These boards are usually supported at a considerable angle to the horizontal so that the ball once projected upon the board will travel by gravity over the board, striking the pins or other obstructions disposed over the surface of the board to direct the balls 25 into the various pockets thereon. Each of the pockets is usually designated with a predetermined scoring value so that those pockets in which it is most difficult to place the balls have the higher scoring values.
- 30 To add further attractiveness to the game, various devices for advancing the scoring values are sometimes provided, and it is an object of my invention to provide a new and novel device for advancing the scoring values of the playing pieces or balls which are projected upon the game board.

Another object of my invention is to provide a game board with a plurality of traps, and means for releasing the ball in at least one of said traps.

Another object of my invention is to provide a game board with a plurality of traps, and with a predetermined pocket on the remaining portion of the board which is adapted to receive a ball 45 therein to operate mechanism for releasing the ball in at least one of said traps to advance the value of said released ball.

Another object of my invention is to provide a simple and novel operating mechanism for determining which one of the plurality of traps is opened and the ball therein released.

Other objects and advantages of my invention will be apparent from, and best understood by the following detailed description of the mechanism illustrated in the accompanying drawings, in which:

Figure 1 is a top plan view of the amusement device constructed in accordance with my invention;

60 Figure 2 is a detailed diagrammatic view of

the electrical circuit and operating mechanisms;

Figure 3 is a detailed vertical sectional view of a portion of the board, taken along the line 3—3 of Figure 1;

Figure 4 is a vertical sectional view taken along the line 4—4 of Figure 3;

Figure 5 is a fragmentary plan view partly in section of the indicator of my invention;

Figure 6 is a vertical sectional view taken along the line 6—6 of Figure 5;

Figure 7 is a vertical sectional view taken along the line 7—7 of Figure 1;

Figure 8 is a vertical sectional view taken along the line 8—8 of Figure 7.

Referring to the drawings, I have illustrated, in Figure 1, a game board apparatus constructed in accordance with my invention, as comprising a suitable, substantially rectangular cabinet 1, the upper surface of which is adapted to be enclosed by means of a top 2 constructed of glass or other transparent material, which will permit a view of the playing board 3 therethrough. The playing board is illustrated as comprising an elongated rectangular board extending from the upper end 4 of the cabinet to a point spaced slightly inwardly of the lower end 5 of the cabinet.

The board 3 forms a main playing field over which play pieces, such as balls, may be projected and is provided with a suitable border construction 6 comprising a substantially curved surface at the upper end of the board and providing relative narrow marginal portions 7 and 8 extending along the extreme sides of the playing field to assist in the guiding of balls over the playing field. A portion of the border member 6 is illustrated as comprising a relatively thin wall 9 which extends along the right-hand side of the playing field but substantially inwardly a short distance from the extreme outer side boundary 7 thereof to constitute therebetween a channel 10 through which balls may be projected by means of a suitable spring projecting mechanism 11 located at the lower right-hand side of the cabinet.

The playing surface of the playing board 3 is provided with a number of holes 12 extending therethrough to constitute play-piece receptacles or ball-receiving pockets distributed in any desired pattern throughout the board. Each of the holes 12 is designated with a predetermined scoring value, dependent upon the difficulty of placing the ball in the particular pocket. To further hinder entrance of balls into the various pockets, I provide pins 13, or other obstructing devices, which will be encountered by the balls, causing them to bound from the pins or obstructions in various directions as the ball passes downwardly over the playing field 3. At the lower end of the playing field there is an elongated

opening 14 which is adapted to receive the balls that are not projected into any of the holes 12 or traps hereinafter mentioned. The opening 14 ordinarily has no scoring value.

5 The end of the playing field 3, adjacent the upper end 4 of the cabinet, is at a considerably higher elevation than that portion of the playing board near the lower end 5 of the cabinet, so that the balls once projected upon the field will 10 tend to move by gravity downwardly over the field, traversing various paths, depending upon the pins which may be encountered by the ball during its passage over the playing field.

The game may be made considerably more attractive by providing a mechanism which may 15 advance the score of one or more of the balls placed in certain receptacles or traps upon the projection of another ball into a selected other pocket. I have provided such a mechanism.

20 In the particular example of my invention disclosed herein, I have provided six traps, 15, 16, 17, 18, 19 and 20. The traps 15, 16, and 17 are formed within suitable guide bars 21 and 22 within which guide bars are also provided ball receiving pockets 25, 26 and 27. The traps 18, 19 and 20 are formed within suitable guide bars 23 and 24 which are similar to guide bars 21 and 22 respectively, and within which are provided ball receiving pockets 28, 29 and 30.

30 The traps ordinarily have no scoring value, but the predetermined scoring values of each of the pockets 25-30 inclusive is ordinarily considerably higher than that of the average of the holes 12. Each of the pockets 25-30 inclusive is designated 35 with a predetermined scoring value, dependent upon the difficulty of placing a ball in the particular pocket, and in the example of my invention disclosed herein, pockets 29 and 30 have the highest scoring values.

40 A second board 35 is mounted immediately below the playing board 3, provided with a plurality of holes 36 and an elongated hole 37 distributed in exactly the same pattern as the pattern of the holes 12, pockets 25-30 inclusive and elongated 45 hole 14, in the playing board 3, but the secondary board is preferably slightly shorter than the playing board 3 so that when the same is in its normal position, as illustrated in Figure 1, the holes 36 and 37 thereof are spaced slightly out of alignment with the holes 12 and 14 and pockets 25-30 50 inclusive on the playing field 3. The secondary board is slidably mounted for movement longitudinally of the cabinet 5 and may be moved toward the upper wall 4 of the cabinet by means of suitable coin-controlled mechanism illustrated 55 at 38, the secondary board 35 being normally urged to move to its normal position shown in Figure 1 by means of suitable springs 39.

When the secondary board 35 is in its normal 60 position, as illustrated in Figure 1, the holes 12 and 14 and pockets 25-30 inclusive constitute pockets or ball-receiving depressions, permitting the balls to be seated therein, resting upon the secondary board 35, but when the secondary board 35 is moved forwardly by the coin-control mechanism 38 the holes 36 and 37 in the secondary board 35 will be aligned with the holes 12 and 14 and pockets 25-30 inclusive, and will allow the balls to drop through the aligned holes to a 65 sub-floor 40.

The sub-floor 40, like the playing board 3 and the secondary board 35, extends at a considerable angle to the horizontal to insure that the balls that drop on the floor 40 will move toward the 70 lower end 5 of the cabinet, ready to be passed to

the projector 11, as will be more fully described hereinafter.

The trap 15 is formed by guide bar 21, spacing bar 41, cross bar 42 and bottom piece 43. Part of the board 3 is cut out in order to provide space for the bottom piece 43 which is hinged to the board 3 by means of a hinge 44 and screws 45. The bottom piece 43 is provided with a slit 46 through which protrudes an extension 47 of contact 48. The lower end of the bottom piece 43 rests upon the upper part of cam 49, which is pivotally mounted upon bracket 50 which in turn is mounted upon the sub-floor 40.

Also mounted upon the sub-floor 40 are bar 51, trip pin 52 and bracket 53. Provided between the bar 51 and the lower part of the cam 49 is a spring 54. Mounted on the bracket 53 is a solenoid 55. In the center of the solenoid 55 behind the solenoid plunger arm 56 is a spring 57 which is adapted to urge the arm 56 outward. The 20 solenoid plunger arm 56 is provided with an extending rod 58, the end of which is enlarged and provided with a stop pin 59. Pivoted in the outer end of the rod 58 is a lever 60, one arm 61 of which is provided with a pawl which is adapted to engage a pin 63 on cam 49, and the other arm 62 of which is at right angles to said arm 61 and is adapted to engage the trip pin 52.

The construction of the other traps is similar 30 to that of trap 15 and will be apparent from the foregoing description. Each of the traps is provided with the operating mechanism just described.

Attached to the upper end of the secondary board 35 are six rods 64 which are adapted to 35 engage the cams 49 and move them forward, and thereby release any balls that may be in said traps when the secondary board 35 is moved forwardly by the coin-control mechanism 38.

By referring particularly to Figures 1 and 2, it 40 will be observed that one of the holes 12, which is indicated by the reference character 65, may be selected as the particular pocket in which a ball may be placed to cause the operation of the trap releasing mechanism.

The secondary board 35 does not extend under the pocket 65 so that a ball placed in this pocket will immediately pass through the pocket 65 to the sub-floor 40. However, an electrical contact mechanism or master switch may be interposed 50 between the playing board 3 and the sub-floor 40, which I have illustrated in the Figure 2. This electrical contact mechanism may be selected of any suitable size, shape or form, so that a ball dropping through the pocket 65 will close 55 an electric circuit, starting the operation of the trap releasing mechanism.

In the form of the device illustrated herein, the master electric contact mechanism consists of a trough 66, pivoted at 67 upon a suitable bearing member 68 secured to the sub-floor 40. The other end 69 of the trough 66 is provided with an arm 70 arranged to engage and close a pair of electrical contacts 71 which will complete a 60 circuit, as shown in Figure 2, extending from an electric battery 72 (preferably a number of dry cells contained within the cabinet) by way of conductor 73, contacts 71, conductor 74, solenoid 75, conductor 76, to the opposite end of the 65 battery 72.

The electric driving means including the solenoid 75 is provided with a plunger arm 77, which is provided with a connecting link 78. Pivoted in the connecting link 78 is an arm 80 which is 70 mounted on a shaft 81, and which is connected 75

to a pin 82 by a spring 83. The shaft 81 extends through the floor 84 of the cabinet 3 and a bushing 86. Mounted on the shaft 81 are ratchet 86, latch wheel 87 and contact wheel 88. The ratchet 86, latch wheel 87 and contact wheel 88 are secured together by means of rivets 89. Mounted upon the arm 80 is a pawl 90 which is adapted to be kept in engagement with the ratchet 86 by means of a spring 91 which is also mounted upon the arm 80.

The latch wheel 87 has six notches 93, which are adapted to be engaged by the end of a spring 94.

The commutating switch or contact wheel 88 has a protrusion 95 which is adapted to engage the contact fingers 96. There are as many notches 93 and contact fingers 96 as there are traps. Each of the contact fingers 96 is connected to an electrical indicator in the form of electric light 97 and to a bimetallic thermostatic switch 98, which is adapted to make contact with a contact member 99 when its elements have been sufficiently heated to cause its operation. Each of the six contacts 99 is connected to a different control switch release or solenoid 55 by means of a conductor 100. A contact finger 101 is adapted to be kept in continuous engagement with the contact wheel 88. The contact finger 101 is connected to the battery 72 by means of conductor 102.

As shown in Figures 2 and 8, the lower end of the sub-floor 40 is provided with a spring 103 which extends through a slot 104 in the sub-floor 40. The spring 103 is adapted to be depressed by a ball resting on the sub-floor 40, thereby closing supervisory switch contact 105. The contact 105 is carried on a bimetallic thermostatic switch arm and heater coil unit 106 which is of such construction that it delays the operation of the contact 105 for a sufficient predetermined length of time after the last ball has been removed from the sub-floor 40 in order to allow the circuit to be closed while said ball is in play.

The circuit extends from battery 72 through conductor 107, the heater coil 106 and normally closed contacts 106' to conductor 126 and back to battery 72. Thus, so long as contacts 106' remain closed by a ball in the slot 104, the heater 106 will be connected in circuit with battery 72, the heater circuit being broken as soon as the last ball moves off of the slot 104 so that contacts 105 will remain closed for a short time until the bimetallic heater arm cools off, whereupon the circuit through lamps 124 and contacts 105 will be broken to battery 72, and the signal means 124 de-energized.

By referring particularly to Figures 7 and 8, it will be understood that when the balls have been played upon the board 3, and have been released by forward movement of the secondary board 35, the balls falling upon the sub-floor 40 will move toward the lower end of the cabinet 1 where these balls will come to rest in a suitable trough 111 preferably extending as shown in Figure 8 at an angle to the horizontal to direct the balls toward the right-hand side of the cabinet 1.

It will be observed, however, that the level of the sub-floor 40 is considerably lower than the level of the playing board 3, and in order to restore the balls to the playing level it is necessary to provide a ball-elevating mechanism. A simple form of ball-elevating mechanism is shown herein as comprising a sector 112 pivoted as at 113 to the board, constituting the right-hand side wall

of the cabinet 1. The sector 112 projects through a suitable slot 114 in the trough 111 to engage the ball 115 lying closest to the right-hand wall of the cabinet 1 at a point slightly to the left of the center of the ball 115. Thus by swinging the sector 112 about its pivot 113 the ball 115 will be lifted by the edge of the sector 112 in a vertical direction until it becomes level with a recess 116 constituting an extension of the channel 10.

It is usual to provide a partition wall 117 in the lower end of the cabinet 1, and this wall may constitute one of the walls of the trough 111 so that the ball will be guided by the partition 117 in a vertical direction. The recess 116 is illustrated in Figure 8 as having its lower surface inclined 15 slightly toward the right-hand side of the cabinet 1 so that once the balls have been lifted up to the recess 116 they will move into the recess and remain therein even though the sector 112 is retracted to its normal position as shown in Figure 7. 20

The sector may be operated in any suitable manner, though I prefer to provide a plunger 118 extending through the lower end 5 of the cabinet and arranged to be pressed inwardly by the person playing the game, the inner end of the plunger 118 engaging one edge of the sector 112 so that the inward movement of the plunger will cause the sector 112 to be rotated to lift the balls one by one into the recess 116. As soon as the pressure is released from the sector 112, it returns to 30 its normal position as shown in Figure 7, due to its construction.

The game may be played in many different ways, one of the preferred ways being as follows:

A coin or other suitable token is placed in the coin control mechanism 38 and pressure is applied to the end of said mechanism which moves the secondary board 35 and the rods 64 forwardly.

The traps 15-21 inclusive are thereby sprung, and the holes in the board 3 are thereby aligned 40 with the holes in the sub-floor 40 which allows the balls to drop through the aligned holes to the sub-floor 40 and down the sub-floor 40 to the trough 111.

The plunger 118 is pressed inwardly and a ball 45 in trough 111 is thereby lifted into the channel 10. The ball in the channel 10 is then projected by the projecting mechanism 11 so as to enter one of the traps 15-21 inclusive. The ball in the trap closes contact 48 of the ball-operated control 50 switch 47-48, and the circuit which extends from battery 72 through conductors 120 and 121, contact 48, conductors 122 and 123, electric light 55 or signal means 124, conductors 125, contact 105 and conductor 126 to the opposite end of the battery 72 is closed, which lights the electric light 124 just below the trap that holds the ball.

The projecting of a ball into one of the traps may be repeated, depending upon the skill of the player until all of the traps 15-21 inclusive are 60 occupied. The balls that are projected but which are not projected into one of the traps come to rest in either one of the holes 12, the elongated hole 14 or pass through the skill hole 65.

When a ball is projected into the skill hole 65, 65 it falls on trough 66 thereby completing an electrical circuit through the master switch as mentioned on page 2, column 2, lines 58-70. The ball rolls off of trough 66 onto sub-floor 40 and back to the trough 111 for replay.

The closing of the above mentioned circuit operates solenoid 75 which causes the rotation of the contact or commutator wheel 88, the latch wheel 87, and the ratchet 86 in a clockwise direction. Just as soon as the contact between contacts 71 is 75

broken, the spring 83 causes the arm 80 to return to its normal position as shown in Figure 2.

The rotation of the contact wheel 88 causes the protrusion 95 to momentarily contact contact fingers 96 and thereby momentarily closes the circuits mentioned on page 3, column 1, lines 44-56 herein, causing one of the lights 97 to flicker, there being six such circuits.

Switches 98 are of such construction that the momentary closing of the above circuits does not cause the operation of said switches.

The thermostatic switches 98 are of such construction that the rotation of the contact wheel 88 causes the thermostatic switch which was in contact with contact 99 to open, thereby allowing the spring 57 to push the solenoid plunger arm 58 outward and pawl lever arm 61 to become in engagement with pin 63 of cam 49.

The rotation of the contact wheel 88, latch wheel 87 and ratchet 85 is finally brought to a stop by means of the braking action of the pawl 98 and the spring 94. The spring 94 is of such construction as to insure the stopping of the latch wheel 87 with the end of the spring 94 in engagement with one of the notches 93 in said latch wheel.

After the contact wheel 88 comes to rest, the steady flow of current through the bimetallic switch 98 causes the switch to rotate and contact contact member 99 and thereby causes the solenoid 55 to operate. The circuit which is closed extends from one end of the battery 12, through conductor 102, contact finger 101, contact wheel 88, contact finger 98, thermostatic switch 98, contact 99, conductor 100, solenoid 55 and back to the opposite terminal of the battery 12 by means of conductor 126.

The operation of the solenoid 55 causes the retraction of solenoid plunger arm 56 which causes the forward movement of the cam 49, thereby allowing the floor piece 43 of the trap to drop and the ball, if any, in said trap to roll from said trap to one of the pockets 25-30 inclusive, depending upon the location of the opened trap. The construction and arrangement of the guide pieces 21-24 inclusive is such that the ball ordinarily falls into the first pocket below the trap, but at times it does not so do, and falls into one of the lower pockets.

As the solenoid plunger arm 56 is retracted, the lever arm 62 engages the trip pin 52 which causes the rotation of the lever 60 to the right and the pin 63 to become free of engagement with the pawl lever arm 61, as the solenoid plunger arm 56 continues to be retracted. The cam 49 is then returned to its original position by means of spring 54, thereby raising the floor piece 43 and closing the trap.

As soon as the ball falls from the trap the contact 48 is opened which opens the circuit the description of which begins on page 3, column 2, line 45 herein, thereby causing the light 124 to go off.

The continued operation of the game will be apparent to those skilled in the art from the foregoing description.

As illustrated in Figures 1 and 3, diamond shaped portions of the board 3 directly below each of the traps 15-21 inclusive may be cut away and differently colored glasses of that shape inserted therein, said glasses being flush with the top surface of the board when inserted therein. The signals or lights 124 are disposed below the diamond-shaped glasses. The glasses may be conveniently numbered as shown in Figure 1, and

the corresponding indicator or light 97 given the same numbers.

As shown in Figures 1, 5 and 6, in order to make the game more attractive, the portion of the board above the electric indicator lights 97 may be cut away in the form of a six-pointed star and a transparent indicator of that shape inserted therein, which when inserted is flush with the top surface of the board.

The design shown in Figure 1 makes a very desirable indicator. The indicator has six main sections, each of which is disposed over one of the lights 97. The transparent surface of the indicator may be colored glass and each section may be of different colored glass. The numerals on the indicator are arranged to correspond with the electrical releasing mechanism so that the numeral which is lit when the latch wheel comes to rest indicates the trap which is released, and corresponds to the numeral below the trap which is released.

For example, the lowest contact finger 96 in Figure 2 is connected to the solenoid 55 located beneath the trap 15. The numeral 1 is placed on the indicator below the light 97 in circuit with the above mentioned contact finger and the same numeral is placed below the trap 15 above the signal light or controlled means 124. The contact fingers beginning to the left of the above mentioned contact finger are connected to the solenoids located below traps 16, 17, 18, 19 and 20 respectively and the lights in circuit with said contact fingers are numbered 3, 5, 2, 4 and 6 respectively, which numerals correspond to the numerals located below the traps respectively, as shown in Figure 1. The glass below the numerals 1 and 2 may be colored red, the glass below numerals 3 and 4 green and the glass below the numerals 5 and 6 yellow, or any other attractive color scheme may be utilized.

In a modification of my device, I have the trap releasing mechanism open two of the traps at once, instead of just one as shown in the drawings. This may be accomplished by the use of a contact wheel 88 having two protrusions 95.

Although I have described my invention with respect to certain particular embodiments thereof, nevertheless I do not desire to be limited to the particular details shown and described except as clearly specified in the appended claims, since many changes, modifications and substitutions may be made without departing from my invention in its broader aspects, which may be found useful in many other applications thereof.

I claim:

1. Control mechanism for pin ball game apparatus, and including a master switch arranged in said game apparatus for operation by a ball, a control switch also arranged in said game apparatus for operation by a ball, and a commutating switch having electrical driving means energized by operation of said master switch, signal means energized by operation of said control switch, a plurality of electrically operable indicators selectively operable by said commutating switch, and means cooperable with said commutator switch when both said master switch and said control switch are operated to render said control switch ineffective for operation by a ball.

2. Control mechanism for use with pin ball game devices and the like, having a predetermined number of balls to be played and including a master switch arranged in said game device for operation by a ball, an electrically operated commutator switch controlled by said master switch,

indicator means operable by said commutator switch, a control switch arranged in said game device for operation by a ball, and signal means operable by said control switch, together with ball-operated switch means for rendering said signal means inoperative after the same has been operated a predetermined length of time by said control switch and after said predetermined number of balls has been played.

10 3. Electrical control mechanism for use with game devices including a propelled and projected instrumentality, said mechanism comprising a master switch arranged in said game device for operation by an instrumentality as aforesaid, an electrically actuated commutator switch controlled by said master switch, a control switch arranged in said game device for operation by an instrumentality as aforesaid, controlled means operable by said control switch, together with means cooperable with said commutator switch for rendering said controlled means inoperative after a predetermined period of operation.

15 4. Control mechanism for pin ball game apparatus, and including a master switch arranged in said game apparatus for operation by a ball, an electrical commutator switch operated by said master switch, a control switch arranged in said game apparatus for operation by a ball, releasable latch means for said control switch and operable to hold a ball in operative relation with respect to said control switch, and electrical latch releasing means operable by said commutating switch.

20 5. Control mechanism for a ball game device, and including a master switch positioned in said game device for operation by a ball, an electrical commutator switch operable by said master switch, a plurality of control switches arranged in said game device for operation by a played ball, releasable holding means for holding a played ball in position to operate a particular control switch, controlled means operable by said control switches, together with electrically operable release means for said holding means and selectively operable by said commutator switch to render said particular control switch inoperative.

25 6. Control mechanism for ball game apparatus, and including a master switch positioned in said game apparatus for operation by a ball, an electrical commutator switch operable by said master switch, a plurality of control switches arranged in said game apparatus for operation by a played ball, releasable holding means for holding a played ball in position to operate a particular control switch, controlled means operable by said control switches, release means for said holding means and delayed action means operable selectively by said commutator switch to release said holding means after said control switch has been operated, whereby said controlled means will be rendered inoperative.

30 7. Control mechanism for game apparatus of the pin-ball type, said mechanism comprising a master switch arranged in said game apparatus for operation by a played ball, a plurality of control switches arranged in said apparatus for operation by a played ball, releasable holding means for holding a played ball in position to operate one of said control switches, electrical release mechanism for said holding means, a commutator switch for selectively operating said electrical re-

lease mechanism, electrical operating means for said commutating switch and operably controlled by said master switch, signal means operable by said control switches, and delayed-action switch means in circuit with said electrical release mechanism and selectively operable by said commutating switch to energize the electrical release mechanism as aforesaid after a lapse of time, responsive to the operation of said master switch by a played ball, whereby said control switches may be rendered inoperative.

35 8. Control mechanism for pin-ball game apparatus and comprising: a plurality of control switches and releasable operating means therefor arranged in the game apparatus for engagement by a played ball and operable to hold a played ball in switch-operating position; electrical release mechanism for each of said operating means; a commutating switch for selectively operating said release mechanism; electrical actuating means for said commutating switch; a master switch arranged in said game apparatus for operation by a played ball and adapted to energize said electrical actuating means of the commutating switch, together with signal means operatively associated with each of said control switches.

40 9. Control mechanism for pin-ball game mechanism and comprising: a plurality of control switches and releasable operating means therefor arranged in the game mechanism for engagement by a played ball and operable to hold a played ball in switch-operating position; electrical release mechanism for each of said operating means; a commutating switch for selectively operating said release mechanism; electrical actuating means for said commutating switch; a master switch arranged in said game mechanism for operation by a played ball and adapted to energize said electrical actuating means of the commutating switch, together with signal means operatively associated with each of said control switches, and thermostatic time-delay switch means operable by said commutating switch and in circuit with said electrical release mechanism for preventing operation of said release mechanism while said commutating switch is being changed.

45 10. Control mechanism for pin-ball game apparatus having a determined number of balls for play, said mechanism comprising: means for storing said determined number of balls for play; a plurality of control switches arranged in said game apparatus and provided with releasable operating means adapted for operative engagement by a played ball and effective to hold said ball in operating position until released; electrical release means for said control switches; signal means selectively operable by said control switches; a power circuit; a ball-operated supervisory switch in said power circuit and arranged in said ball storing means to render said signal means operable so long as one of said determined number of balls is in said storing means, and means for selectively operating said release means and including a commutating switch and electrical drive means therefor for selectively connecting said release means in said power circuit, together with a master switch in said power circuit and arranged in said game apparatus for operation by a played ball and effective to energize said commutating switch drive means.

70
